(57) **CLAIM**

The ornamental design for an inlet shield, as shown and described.

DESCRIPTION

FIG. 1 is a perspective view of an inlet shield showing our new design;

FIG. 2 is a perspective view of a first portion of the inlet shield shown in FIG. 1 being decoupled from the second portion of the inlet shield;

FIG. 3 is a front view of the first portion of the inlet shield shown in FIG. 1;

FIG. 4 is a back view of the first portion of the inlet shield shown in FIG. 1;

FIG. 5 is a first side view of the first portion of the inlet shield shown in FIG. 1;

FIG. 6 is a second view of the first portion of the inlet shield shown in FIG. 1;

FIG. 7 is a front view of the second portion of the inlet shield shown in FIG. 1;

FIG. 8 is a back view of the second portion of the inlet shield shown in FIG. 1;

FIG. 9 is a first side view of the second portion of the inlet shield shown in FIG. 1;

FIG. 10 is a second view of the second portion of the inlet shield shown in FIG. 1;

FIG. 11 is a side view of the inlet shield shown in FIG. 1; and,

FIG. 12 is a perspective view of an inlet shield shown in FIG. 1 with environment.

The keyring and chain shown in broken lines show environment and all remaining broken lines show portions of the inlet. All broken lines form no part of the claimed design.

1 Claim, 8 Drawing Sheets
